UNITED STATES PATENT OFFICE

169,928

LINGERIE HOLDER

Helen Louise Button, Chicago, Ill.

Application August 8, 1952, Serial No. 20,944

Term of patent 14 years

(Cl. D17—3)

To all whom it may concern:

Be it known that I, Helen Louise Button, a citizen of the United States, residing at Chicago, Illinois, have invented a new, original, and ornamental Design for a Lingerie Holder, of which the following is a specification, reference being had to the accompanying drawing, forming a part hereof:

Fig. 1 is a front elevational view of a lingerie holder, showing my new design;

Fig. 2 is a top plan view thereof; and

Fig. 3 is a perspective view thereof with the central clip shown in open condition and with the end clips and portions of the chain being broken away for convenience of illustration.

The dominant features of my design reside in those portions shown in full lines.

I claim:

The ornamental design for a lingerie holder, substantially as shown and described.

HELEN LOUISE BUTTON.
